ALBERT E. DIETERICH, OF WASHINGTON, DISTRICT OF COLUMBIA, ASSIGNOR OF ONE-HALF
TO FRED G. DIETERICH, OF WASHINGTON, DISTRICT OF COLUMBIA.

VENDING-MACHINE.

No. 921,597.

Specification of Letters Patent.

Patented May 11, 1909.

Application filed February 8, 1909. Serial No. 476,813.

To all whom it may concern:

Be it known that I, ALBERT E. DIETERICH, residing at Washington, in the District of Columbia, have invented certain new and useful Improvements in Vending-Machines, of which the following is a specification.

My invention is an improved vending machine and in its generic nature the invention embodies an improved coin mechanism, an improved strip guiding mechanism, an improved coin chute, an improved automatic chute closer and certain improvements in the coin insertible end of the casing.

In the art as practiced today there has come into use a vending machine for selling postage stamps, soda checks and the like in which the vendable article is contained in the form of a continuous strip, which strip is formed by folding a paper lengthwise upon itself and gumming the same at intervals to separate the strip into pockets. It is customary to omit the gumming in some instances, such as when the strip is to be used as a soda check. When the strip is used as a stamp selling strip, however, the pockets are formed between the gummed parts of the strip. The strip is also perforated at intervals to co-act with the feeding mechanism of the vending machine. In such vending machine the sales strip is fed step by step and the vended part is severed from the remainder of the strip at predetermined intervals. Such machine in its make-up embodies a rotatable operating shaft, a trip coin mechanism controllable from such shaft, a strip feeding mechanism controllable from the operating shaft and a cutting mechanism also controllable from the operating shaft, the several mechanisms being timed to co-act at the desired intervals. The coin mechanism used in the foregoing machine comprises a pusher, a dog for locking the shaft from rotation under inoperative conditions, the pusher and dog each having coordinate parts for catching a coin from the coin chute and holding it to lock the pusher and dog together, while a trip on the operating shaft engages a projection on the pusher, (either directly or indirectly) and moves the pusher forward on its stroke to release the dog from its locking engagement with the shaft. This movement is practically instantaneous, and is imparted during only a small fraction of the rotatable move-

ment or cycle of operation of the rotatable shaft since as soon as the shaft trip has engaged the pusher and moved the pusher to the limit of its stroke, the shaft trip disengages the pusher and the pusher is instantly returned by a spring to its normal position, 60 the locking dog, however, does not fall into its normal position in the locking notch of the shaft until near the end of the rotatable cycle of the operating shaft, thereby leaving an open pass through the coin mechanism 65 of the machine during approximately more than three-fourths of the revolution of the operating shaft. This makes it necessary to insert but one coin at a time in the machine and carry the operating shaft through 70 its complete cycle of movement before inserting a second coin, otherwise such second coin (and subsequent ones) will pass through the open pass of the coin mechanism and be lost. To overcome this objectionable feature is one of the principal objects of my present invention.

In the machine above referred to the continuous envelop is fed from the reel to the feeding roll by what is known as the "under feed", i. e., the strip leaves the roll at the bottom and goes up an incline and then down over the feeding drum. This sometimes (when the continuous envelop is not gummed to separate the pockets) causes the 85 stamps or inserts to slip from one pocket to another, and hence disarrange the sales. A further object of my invention is to overcome this objection.

My invention also has for its object to provide an improved means for closing the coin chute when the machine is emptied or sold out so that a prospective purchaser may not insert his coin when the machine cannot deliver the goods.

Another object of my invention is to improve the coin passage of the machine so that a straight coin chute may be used.

In carrying out the foregoing objects of my invention I provide a pusher having cooperative connection with the rotatable drive shaft whereby the pusher will be moved by the drive shaft to the limit of its stroke in one direction and not released to come back on its return stroke until the dog has entered 105 its locking notch on a rotatable shaft member. In other words the dog is returned to its locking position before the pusher starts

on its return movement. I further provide the pusher with a cut-off that projects beneath the coin slot after the pusher starts on its working stroke. I also provide means whereby the pusher and dog may have adjustable devices so that a coin of a predetermined size only will actuate the mechanism.

In improving the strip guide I have provided means whereby an over-feed in the sales strip to the feeding mechanism is maintained at all times and whereby the strip as it leaves the reel and passes toward the feeding mechanism may be maintained, as nearly as practicable, in a horizontal position at all times to prevent slipping of the inserts from one pocket to another. This is accomplished by providing a table over which the strip is fed to the feeding mechanism and a guard which holds the strip down on the table.

My improved slot locking mechanism consists of a pin or member projectable into the coin slot to prevent passage of a coin therethrough, the projectable member being held out of the slot by a rod that engages the paper strip but drops when the strip has passed from under the rod and through the medium of a bell crank lever, or its equivalent, moves the projecting member into the coin slot.

My present invention also resides in those novel details of construction, combination and arrangement of parts all of which will be first fully described, then be specifically pointed out in the appended claims, and illustrated in the accompanying drawings, in which:

Figure 1, is a rear elevation of the support and the mechanism carried on the back thereof. Fig. 1^a, is a detail view of the back check pawl and ratchet mechanism carried by the operating shaft to limit its movement in one direction, showing the position of the pawl and ratchet when the coin mechanism parts are in the position shown in Fig. 1. Fig. 2, is a view similar to Fig. 1, the rotatable operating shaft having been turned to bring the coin mechanism into its first or dog releasing position. Fig. 2^a, is a view similar to Fig. 1^a, showing the position of the back check mechanism for the operating shaft when such shaft is in the position shown in Fig. 2. Fig. 3, shows the position of the coin mechanism when the coin pusher has reached the limit of its stroke and is locked. Fig. 3^a, shows the position of the back check ratchet and pawl when the rotatable operating shaft and the other parts are in the position shown in Fig. 3. Fig. 4, is a detail plan section on the line 4—4 of Fig. 3. Fig. 5, is a plan view of the coin pusher. Fig. 6, is an inverted plan view of one end thereof. Fig. 7, is a detail elevation of the removable

gear piece that forms a part of the pusher. Fig. 8, is a detail perspective view of the locking dog. Fig. 9, is a detail elevation of the insertible plate on which is adapted to be mounted the bulk of my coin mechanism. Figs. 10, 11, 12 and 13, are sections on the lines 10—10; 11—11; 12—12 and 13—13, respectively of Fig. 9. Fig. 14, is a detail elevation of a modification of my invention. Fig. 15, is a detail plan view of a portion thereof. Fig. 16, is a front elevation of a part of the support showing the strip feeding and guiding mechanism. Fig. 17, is a detail view partly in section of the coin chute closing mechanism. Fig. 18, is a top plan view thereof. Fig. 19, is a central vertical cross section of the upper part of the machine showing the coin insertible opening in the casing and the coin guide that co-operates therewith. Fig. 20, is a top plan view of what is shown in Fig. 19. Fig. 21, is a detail view of a modification when two coins are necessary to operate the coin mechanism.

Referring now to the accompanying drawings in which like letters and numerals of reference indicate like parts in all of the figures, I will first indicate those parts of the machine which are old in the art and which, *per se*, constitute no part of my invention. Such old parts consist of the supporting frame 1, which has a cut-away portion or opening 22. The frame 1 has a bearing to support the rotatable operating shaft 3, whose movement is limited to one direction by the ratchet and pawl mechanism disclosed in Figs. 1^a, 2^a and 3^a, respectively. 6 designates a cam member mounted on the shaft 3 to turn therewith, and the cam member 6 has a notch 63 for the locking dog to enter.

2 represents the feeding shaft which is geared with the shaft 3 by mutilated gear connections 4—5.

The support 1 has a web 14 to prevent coins from interfering with the mechanism above the web, and is also provided with a bearing 11 for the cutter shaft 10 on which the cutter bell crank lever 7 is mounted, the bell crank lever 7 having a portion 8 provided with an anti-friction roller 9 that is adapted to enter the cam groove 9^x in the cam member 6. The bell crank lever 8 carries the cutter 12 that co-operates with the fixed cutter 13. The back check mechanism for the shaft 3 consists of a disk 73 having an internal ratchet face 74 to be engaged by a pawl 76, pivoted at 77, to a fixed stud that may be secured to the web or support 1 in any approved manner. In adapting the back check mechanism to my improved coin mechanism I find it advisable to insert an additional ratchet tooth 75, as shown in the drawings.

On the drum shaft 2 on the front side of the web 1 is a feed drum 15 which is guarded by an encircling guard 16 and a stripping

guard 19 between which the continuous envelop 89 passes, the guard 16 being secured at 17 and 18, as indicated.

A bearing 20 is provided for the slot closure rod 120.

21 designates the delivery slide onto which the severed sections of the envelop are delivered and from which they are ejected from the machine.

10 Those parts designated by the numerals 1 to 22 inclusive and by the numerals 73, 74, 76 and 77 inclusive, *per se*, form no part of my present invention, as they are parts of the machine hereinbefore described as being 15 known in the art. My invention consists in the provision of the parts other than those numbered as just above referred to. By reference to Figs. 1 to 3 of the drawings my improved coin mechanism will be readily understood.

20 In carrying out my invention I close the aperture 22 by an insert plate 23, shown in detail in Fig. 9, the plate 23 having lugs 24, 25, 26 and 31 which overlap the web or support 1 and which may be riveted thereto to form an integral part thereof. The plate 23 is also provided with a table 28, whose forward end is downwardly bent as at 29, a lug 30 being also provided for a purpose presently to appear, and the lug 26 is also provided with a projecting wall 27 for a purpose which will also be hereinafter made apparent.

25 My improved pusher 37 is shown in detail in Figs. 5, 6 and 7, and comprises the arm 35 cut away as at 44 to receive the head of the pivot screw 36 that screws into a bearing lug 99, cast integral with the web or support 1, the web 14 being notched out to receive the pusher rod 37.

30 39 designates the coin slot or passage of the pusher 37 and 42 and 44 designate slots, one for the securing screw 47 and the other for the screw 36, so as to retain the pusher in position and at the same time permit reciprocating movement to be imparted thereto.

35 38 designates the gate or cut-off of the pusher and 41 represents a heel that is adapted to engage a bumper 59 to render the operation of the machine as noiseless as possible.

40 A set screw 60 co-operates with the coin slot 39 of the pusher and through the medium of the set screw 60 the pusher may be adjusted to take a coin of only a predetermined size.

45 The dog 61 which co-operates with the depression 63 of the cam 6 to lock the shaft 3 normally from rotation is another part of my improved coin mechanism, the dog 61 being pivoted by a screw 62 that enters the lug 31 of the plate 23, which lug forms a bearing for the screw 62. The dog 61 has a downwardly projecting portion merging with a rearwardly projecting portion 64 that is slotted at 65 to

receive the coin in its passage through the machine, an adjusting screw 66 being provided to co-operate with the screw 60 to adjust the mechanism for a particular coin.

50 The coin chute 68 is undercut to form a shoulder 69 beneath which the projection 64 of the dog 61 is located for a purpose presently to appear.

55 The dog 61 is normally held in engagement with the cam 6 by gravity or by a spring 67.

60 The pusher rod 37 at its forward end has its arm 35 provided with a hardened steel piece 48 that is secured to the arm 36 in a socket to be flush with the front face of the arm 35 and the steel piece is provided with a notch 49 to form a tooth 51 whose other side is formed by a depression 50 of greater depth than the notch 49 to co-operate with the tooth 54 on a disk 52 secured at 53 to the face of the cam 6. The disk 52 has a shoulder or toothed portion 55 to co-operate with that 50 of the toothed steel piece 48, the pusher 37 also having a curved part 46 to co-operate with the curved surface 56 of the disk 52, the curved surface 56 extending through an arc of approximately 270° and merging with a mutilated portion 57 that projects at the tooth 54.

65 The pusher 37 and the piece 48 has a curved or beveled under-surface 71 to co-operate with an adjustable support 70 at times, the support 70 having a curved or beveled face 72 to contact the surface 71 of the pusher when the pusher is at the limit of its working stroke. The pusher is adapted to 70 be returned and retained in its normal position with the coin slot 39 under the chute 68, by a coil spring 58.

75 The strip is fed from the reel to the strip feeding mechanism. I provide a spindle 32 on the plate 23 on which the roller 84 that carried the reel 86 is mounted, the spindle and reel being held in place by a wire clip 33 that is pivoted at 34 onto the plate 23 in the usual manner. A table 81 is provided that 80 lies in a horizontal plane at the uppermost level of the feeding mechanism which consists of the drum 15 and the bearing for the shaft 3 over which the strip passes. The table 81 is secured by a plate 83 to the web or support 1, and has its forward end 82 curved to prevent tearing the strip. A guard 78 co-operates with the table 81 to hold the strip down on the table and also to guide the strip from the top of the full roll 86, see dot and dash lines in Fig. 16, over the table 81, the guard 78 having ears 79 through which the guard may be secured to the web or support 1.

85 designates the end of the reel 76, and by reference to Fig. 16, it will be noticed that 90 the table 81 is supported on a plane between the top of the full reel 86 and the bobbin 84 so as to maintain the paper through its pas-

sage from the reel into the feeding mechanism as nearly horizontal as practicable at all times.

I also provide a guard 87 to engage the projected end 89 of the sales strip, as it is fed between the cutters 12 and 13, the guard 87 being bent up at the front end or down at the front end as conditions may require. By bending the guard up at the front end any tendency of the paper to feed laterally toward the support 1 is obviated, or should the projecting end have a tendency to feed the paper away from the table or support by bending the forward edge of the guard 87 down this will be compensated for, the guard 87 being secured at 88, as indicated.

In the modified form of coin mechanism disclosed in Fig. 14, the construction of the pusher 37 is the same as in the other figures except that the screw 36 may be omitted. In this form of my invention I provide the pusher with a stud 96 to be engaged by the fork 95 of the bell crank lever 94, pivoted through its bearing 91 on a screw 92 that enters a fixed part of the supporting frame, and the bell crank lever has its other leg 93 projected across the face of the cam disk 6, which cam disk has a pin 90 to engage the leg 93 of the bell crank lever, the parts being in their normal position, as shown in Fig. 14. When the shaft 3 is turned in the direction of the arrow in Fig. 14, during the first movement that takes place the pin 90 moves to the position 97 to rock the bell crank lever to the position shown in heavy dotted lines in Fig. 14, to move the pusher forward a corresponding distance to move the coin 100 to the position shown in 101 in heavy dotted lines, thus elevating the dog 61 out of the notch on the disk 6 and permitting further movement on the shaft 3. As the shaft 3 is turned with the pin 90 from the position 97 in Fig. 14, to the position 98 in Fig. 14, the balance of the movement of the pusher 37 will be effected and the coin moved to the position 102 where it is dropped or ejected. About the same time the dog 61 again enters the notch in the cam or disk 6 and as the shaft 3 is turned to complete its revolution to move the pin 90 from the position 98 back to its original position the spring that is secured to the pusher will return the pusher to its original position and permit the next coin to drop into operative position.

My improved coin slot closer is shown in detail in Figs. 17 and 18, by reference to which it will be seen that a block 105 secures the coin chute 68 to the support 1. The block 105 has a bearing 106 for a pin 107 that engages the fork 109 of a bell crank lever 108 which is pivoted at 111 to the block 105 and connects with the rod 120, see Figs. 17 and 18, it being understood that the rod 129 is bent at the necessary places

to cause it to conform to the configuration of the casing in which the works are inserted. So long as the sales strip is under the rod 120 (see Fig. 16) the bell crank lever 108, will be maintained in the position shown in Fig. 17, to prevent the rod or pin 107 from being inserted in the coin slot 68, but when the end of the sales strip or envelop passes from beneath the rod 120, see Fig. 16, such rod will drop, thereby causing the bell crank lever 108 to rock on its pivot and project the pin 107 into the coin slot 68, and thus prevent a coin being inserted.

The works of this machine are adapted to be inserted in a suitable case, the upper or coin passage portion of which is shown in Figs. 19 and 20, by reference to which it will be seen that the case 112 carries a coin piece holder 114, milled at 115, to the size of the desired coin, the milled portion 115 merging with the back end of a cut-away part 113 in the top of the case 112, and being held in alignment with the coin chute 68. The front of the case 116 is provided with a lip 117 to cover so much of the cut-away part 113 as is in advance of the coin holder 114, see Fig. 19. This makes it easy to provide the insert opening through the top of the case 112 without the necessity of boring or cutting a slot the size of a coin therein.

Operation: I will first describe the operation of the coin mechanism. This will be best understood by reference to Figs. 1 to 3 inclusive of the drawings, which show the three cardinal positions of the mechanism. Normally the parts are positioned as shown in Fig. 1. A coin is dropped into the chute 68 and gravitates to the position shown in Fig. 1, the operator turning the shaft 3 (through a handle or any other equivalent means) causes the shaft 3 to be turned in the direction of the arrow in Fig. 1. The first thing that takes place, is that the tooth 54 engages the tooth 51 and locks the pusher to the disk 52, the movement of the shaft 3 from the position shown in Fig. 1 to that shown in Fig. 2, causing the pusher to be reciprocated in the direction of the arrow in Fig. 2, from the position shown in Fig. 1 to that shown in Fig. 2, to bring the coin 100 under the projecting part 64 of the dog 61 and raise the end out of the notch 63 in the cam 6, thereby unlocking the shaft, it being understood that the movement of the shaft 3 from the position shown in Fig. 1, to that shown in Fig. 2, is always accessible as free movement.

It is to be noticed that the coin while the parts are positioned as shown in Fig. 2, is held on the table end 29 by the foot of the dog 61, and does not become ejected at this time. A further turning of the shaft 3 from the position shown in Fig. 2 to that shown in Fig. 3, causes the pusher 37 to be moved

from the position shown in Fig. 2 to the position shown in Fig. 3, which is the limit of its movement. At this time the curved surface 56 of the disk 52 enters the curved 5 part 46 of the pusher and locks the pusher from reciprocation in either direction. The pusher remains locked until the shaft 3 has about completed its cycle of movement and the mutilated portion 57 comes over the 10 pusher when the pusher will be released and brought back to the position shown in Fig. 1, by the spring 58, it being understood that from the time the pusher leaves the position shown in Fig. 1, until it again arrives at such 15 position the cut-off or slide 38 will be under the coin chute 68 and prevent a second coin dropping into place. The web 27 of the lug 26 acts in connection with the web 14 as a guard. 20 Should it be attempted to operate the coin mechanism with a coin smaller than that of the predetermined size but large enough not to run through the pass of the coin mechanism by holding the coin in any manner between the pusher and the projection 64 of the dog so as to elevate the dog out of its locking notch, such action will cause the projection 64 to engage the shoulder 69 and lock the pusher from further movement, 30 thus preventing a smaller coin operating the machine.

During the first turn of the shaft 3, through the first part of its cycle of movement, the shaft 2 will be rotated to feed a 35 section of the continuous strip through the cutting mechanism, after which the shaft 2 will cease its turning and a further movement of the shaft 3 will actuate the cutting mechanism to sever the projecting part of 40 the strip in the usual manner.

The modified form of coin mechanism disclosed in Fig. 14, operates similar to that shown in Figs. 1 to 3, inclusive with this exception that the return of the pusher 37 45 from the limit of its movement in one direction to its initial position is instantaneous after the mutilated part of the disk 52 alines with the pusher, whereas in the form shown in Fig. 14 the return of the pusher is gradual. 50 This is accomplished in the following manner: The first movement of the shaft 3 in the direction of the arrow in Fig. 14, from the position 90 to the position 97 unlocks the dog 61; a further movement from the position 55 97 to the position 98 ejects the coin from beneath the dog; also the dog 61 drops into its notch on the screw 60 and the movement from the position 98 back to the position 90 immediately restores the pusher 37 60 to its normal position, to allow a second coin to come into place.

Actual demonstration by the use of a machine constructed as shown in the drawings of this application has proved that perfect 65 operation may be had and as many as eight

coins may be inserted in the chute before the shaft 3 is turned and that a continuous turning of the shaft 3 so long as any coin is in the chute will perform successive operations in the mechanism. For instance, if seven 70 coins are placed in the chute and the operator then begins to turn the shaft 3 he can keep on turning until seven strip sections are delivered to him, but no longer.

From the foregoing description taken in 75 connection with the accompanying drawings it is thought the complete construction, operation and many advantages of my invention will be readily understood by those skilled in the art to which the invention 80 appertains.

What I claim is:

1. A coin mechanism for vending machines comprising a rotatable operating shaft, a locking dog to prevent rotation of such shaft 85 in one direction, means preventing rotation of the shaft in an opposite direction, a coin pusher, said locking dog and said coin pusher having coöperating coin engaging portions, and means carried by the operating shaft 90 for engaging the pusher to move it in one direction and prevent its return until the locking dog is returned to its initial position.

2. A coin mechanism for vending machines comprising a rotatable operating shaft, a dog 95 for locking said shaft from rotation in one direction, a coin pusher, said pusher and said dog having coin engaging portions combined with means for connecting the operating shaft with the pusher to cause said operating shaft to move said pusher to the limit of its movement in one direction, and means for permitting said dog to be restored to its initial position before the pusher starts on its return stroke.

3. A coin mechanism for vending machines comprising a rotatable operating shaft, a dog engaging a notched member on said operating shaft to prevent rotation of said shaft in one direction, a coin pusher, said pusher and said dog engaging a coin, combined with means carried by the operating shaft to engage the coin pusher and move it in one direction to first release the dog from engagement with the operating shaft and then upon further movement eject the coin and lock the pusher from movement during a predetermined time.

4. A coin mechanism for vending machines comprising a rotatable operating shaft, a dog 120 engaging a notched member on said operating shaft to prevent rotation of said shaft in one direction, a coin pusher, said pusher and said dog engaging a coin, combined with means carried by the operating shaft to engage the coin pusher and move it in one direction to first release the dog from engagement with the operating shaft and then upon further movement eject the coin and lock the pusher from movement during a predetermined 125 130 time.

time, and means for releasing said pusher to return to its initial position after the locking dog has been restored to its initial position.

5. A coin mechanism for vending machines comprising a uni-directionally rotatable operating shaft having a member provided with a dog receiving notch, a dog adapted to engage said notch to prevent rotation of the operating shaft in one direction, said operating shaft having a limited movement independent of the dog in such direction, a coin pusher, said dog having a member projected into the path of the coin as it is moved by the pusher to release the dog, combined with 10 means actuated from the rotatable operating shaft for first moving the pusher in one direction to cause the coin to engage the dog and release it from its notch and upon further movement of the operating shaft to cause 15 further movement to be imparted to the pusher to eject the coin, and means for preventing the pusher being restored to its initial position until the locking dog enters its locking notch in the rotatable shaft member.

25. 6. A coin mechanism for vending machines, comprising a uni-directionally rotatable operating shaft having a member provided with a dog receiving notch, a dog adapted to engage said notch to prevent rotation of the operating shaft in one direction, said operating shaft having a limited movement independent of the dog in such direction, a coin pusher, said dog having a member projected into the path of the coin 30 as it is moved by the pusher to release the dog, combined with means actuated from the rotatable operating shaft for first moving the pusher in one direction to cause the coin to engage the dog and release it from its 35 notch and upon further movement of the operating shaft to cause further movement to be imparted to the pusher to eject the coin, means for preventing the pusher being restored to its initial position until the locking 40 dog enters its locking notch in the rotatable shaft member, and means for releasing said pusher after the dog has entered said notch.

45. 7. A coin mechanism for vending machines, comprising a uni-directionally rotatable operating shaft, a member carried by said shaft having a dog engaging notch or slot, a dog adapted to engage said member in said slot, said shaft having a limited movement independent of the dog, a coin 50 pusher, said coin pusher and said dog having coin engaging portions combined with means actuated from the rotatable operating shaft for positively moving the pusher in one direction and preventing said pusher from being restored to its initial position until the locking dog has again entered its notch, and means for restoring said pusher to its initial 55 position.

60. 8. A coin mechanism for vending machines

comprising a uni-directionally rotatable operating shaft, a member carried by said shaft having a dog engaging notch or slot, a dog adapted to engage said member in said slot, said shaft having a limited movement independent of the dog, a coin pusher, said coin 65 pusher and said dog having coin engaging portions combined with means actuated from the rotatable operating shaft for positively moving the pusher in one direction and preventing said pusher from being restored to its initial position until the locking dog has again entered its notch, and means independent of the rotatable operating shaft for restoring said pusher to its initial 70 position.

9. A coin mechanism for vending machines comprising a rotatable operating shaft, a locking dog to prevent rotation of such shaft in one direction, means preventing rotation of the shaft in an opposite direction, a coin 85 pusher, said locking dog and said coin pusher having co-operating coin engaging portions, means carried by the operating shaft for engaging the pusher to move it in one direction and prevent its return until the locking dog 90 is returned to its initial position, a coin chute adapted to deliver a coin into the coin engaging portion of such pusher and a gate carried by the pusher to cut off the outlet of the chute when the pusher is out of its initial or 95 normal position.

10. A coin mechanism for vending machines comprising a rotatable operating shaft, a dog for locking said shaft from rotation in one direction, a coin pusher, said 100 pusher and said dog having coin engaging portions combined with means for connecting the operating shaft with the pusher to cause said operating shaft to move said pusher to the limit of its movement in one 105 direction, means for permitting said dog to be restored to its initial position before the pusher starts on its return stroke, a coin chute adapted to deliver a coin into the coin 110 engaging portion of such pusher, and a gate carried by the pusher to cut off the outlet of the chute when the pusher is out of its initial or normal position.

11. A coin mechanism for vending machines comprising a rotatable operating 115 shaft, a dog engaging a notched member on said operating shaft, to prevent rotation of said shaft in one direction, a coin pusher, said pusher and said dog engaging a coin, combined with means carried by the operating shaft to engage the coin pusher and move it in one direction to first release the dog from engagement with the operating shaft and then upon further movement eject the coin and lock the pusher from movement 120 during a predetermined time, a coin chute adapted to deliver a coin into the coin engaging portion of said pusher and a gate car- 125

ried by the pusher to cut off the outlet of the chute when the pusher is out of its initial or normal position.

12. A coin mechanism for vending machines comprising a rotatable operating shaft, a dog engaging a notched member on said operating shaft to prevent rotation of said shaft in one direction, a coin pusher, said pusher and said dog engaging a coin, combined with means carried by the operating shaft to engage the coin pusher and move it in one direction to first release the dog from engagement with the operating shaft and then upon further movement, eject the coin

15 and lock the pusher from movement during a predetermined time, means for releasing said pusher to return to its initial position after the locking dog has been restored to its initial position, a coin chute adapted to deliver a coin into the coin engaging portion of said pusher, and a gate carried by the pusher to cut off the outlet of the chute when the pusher is out of its initial or normal position.

13. A coin mechanism for vending machines comprising a uni-directionally rotatable operating shaft having a member provided with a dog receiving notch, a dog adapted to engage said notch to prevent rotation of the operating shaft in one direction, said operating shaft having a limited movement independent of the dog in such direction, a coin pusher, said dog having a member projected into the path of the coin as it is moved by the pusher to release the dog,

35 combined with means actuated from the rotatable operating shaft for first moving the pusher in one direction to cause the coin to engage the dog and release it from its notch and upon further movement of the operating shaft to cause further movement to be imparted to the pusher to eject the coin, means for preventing the pusher being restored to its initial position until the locking dog enters its locking notch in the rotatable shaft member, a coin chute adapted to deliver a coin into the coin engaging portion of said pusher, and a gate carried by the pusher to cut off the outlet of the chute when the pusher is out of its initial or normal position.

50 14. A coin mechanism for vending machines, comprising a uni-directionally rotatable operating shaft having a member provided with a dog receiving notch, a dog adapted to engage said notch to prevent rotation of the operating shaft in one direction,

55 said operating shaft having a limited movement independent of the dog in such direction, a coin pusher, said dog having a member projected into the path of the coin as it is moved by the pusher to release the dog, combined with means actuated from the rotatable operating shaft for first moving the pusher in one direction to cause the coin to engage the dog and release it from its notch,

and upon further movement of the operating shaft to cause further movement to be imparted to the pusher to eject the coin, means for preventing the pusher being restored to its initial position until the locking dog enters its locking notch in the rotatable shaft member, means for releasing said pusher after the dog has entered said notch, a coin chute adapted to deliver a coin into the coin engaging portion of said pusher, and a gate carried by the pusher to cut off the outlet of the chute when the pusher is out of its initial or normal position.

15. A coin mechanism for vending machines, comprising a uni-directionally operating shaft, a member carried by said shaft having a dog engaging notch or slot, a dog adapted to engage said member in said slot, said shaft having a limited movement independent of the dog, a coin pusher, said coin pusher and said dog having coin engaging portions combined with means actuated from the rotatable operating shaft for positively moving the pusher in one direction and preventing said pusher from being restored to its initial position until the locking dog has again entered its notch, means for restoring said pusher to its initial position, a coin chute adapted to deliver a coin into the coin engaging portion of said pusher, and a gate carried by the pusher to cut off the outlet of the chute when the pusher is out of its normal or initial position.

16. A coin mechanism for vending machines comprising a uni-directionally operating shaft, a member carried by said shaft having a dog engaging notch or slot, a dog adapted to engage said member in said slot, said shaft having a limited movement independent of the dog, a coin pusher, said coin pusher and said dog having coin engaging portions combined with means actuated from the rotatable operating shaft for positively moving the pusher in one direction and preventing said pusher from being restored to its initial position until the locking dog has again entered its notch, means independent of the rotatable operating shaft for restoring said pusher to its initial position, a coin chute adapted to deliver a coin into the coin engaging portion of such pusher and a gate carried by the pusher to cut off the outlet of the chute when the pusher is out of its initial or normal position.

17. A coin mechanism for vending machines comprising a rotatable operating shaft, a coin pusher and a dog coöperating with the shaft to prevent rotation of said shaft in one direction, said dog and said coin pusher having coin engaging members, and means for actuating said pusher from said rotatable operating shaft, combined with means independent of the operating shaft for engaging the dog and limiting the movement

thereof to lock the dog and pusher together through the medium of a coin and prevent operation of the mechanism at times.

18. A coin mechanism for vending machines, comprising a rotatable operating shaft, a coin pusher and a dog coöperating with the shaft to prevent rotation of said shaft in one direction, said dog and said coin pusher having coin engaging members, means for actuating said pusher from said rotatable operating shaft, combined with means independent of the operating shaft for engaging the dog, and limiting the movement thereof to lock the dog and pusher together through the medium of a coin and prevent operation of the mechanism, said last named means comprising a fixed member adapted to be engaged by a coin part of the dog at times.

20 19. A coin mechanism for vending machines, comprising a rotatable operating shaft, a coin pusher and a dog coöperating with the shaft to prevent rotation of said shaft in one direction, said dog and said coin pusher having coin engaging members, means for actuating said pusher from said rotatable operating shaft, combined with means independent of the operating shaft for engaging the dog and limiting the movement thereof to lock the dog and pusher together through the medium of a coin and prevent operation of the mechanism at times, said last named means comprising a coin chute having an under-cut portion to engage the coin engaging member of the dog at times.

20. A coin mechanism for vending machines, a uni-directionally operating shaft, a member on said shaft having a cut-away portion or depression, a pivoted dog to engage said member in said depression to lock the shaft from rotation, a coin pusher having a coin receiving portion, said dog having a portion provided with a coin receiving portion held in the path of movement of the coin to be engaged by said coin at times, a table beneath said pusher on which said coin is adapted to rest at times, a coin chute for delivering the coin to the pusher, a toothed piece carried by the pusher, a disk carried by the operating shaft to engage said toothed piece of the pusher at times to reciprocate said pusher in one direction, said disk and said pusher having portions for interlocking to hold the pusher from being restored to its initial position during a predetermined interval, and said disk having projections for releasing said pusher at times, and means for restoring said pusher to its initial position when released.

21. In a coin mechanism for vending machines, a unidirectionally operating shaft having a member provided with a cut-away portion, a dog coöperating with said member

at said cut-away portion to lock the shaft 65 from turning, a pusher having a coin receiving portion, means for conveying a coin to said pusher, said dog having a member projected in the path of movement of said coin when moved by the pusher, a table beneath 70 said pusher on which said coin is adapted to rest, means tending to move the pusher to the initial position, said pusher having a cut-off to coöperate with the coin delivery means, means actuated by said rotatable operating 75 shaft for moving said pusher in one direction to cause said coin to engage said dog carried coin engaging member to release the dog, and upon further movement to eject the coin and prevent said pusher from being restored 80 to its initial position until the coin has been ejected and the dog restored to its initial position.

22. In a coin mechanism for vending machines, a unidirectionally operating shaft 85 having a member provided with a cut-away portion, a dog coöperating with said member at such cut away portion to lock the shaft from turning, a pusher having a coin receiving portion, means for conveying a coin to 90 said pusher, said dog having a member projected in the path of movement of said coin when moved by the pusher, a table beneath 95 said pusher on which said coin is adapted to rest, means tending to move the pusher to the initial position, said pusher having a cut-off to coöperate with said coin delivery means, means actuated by said rotatable operating shaft for moving said pusher in one direction to cause said coin to engage 100 said dog carried coin engaging member to release the dog and upon further movement to eject the coin and prevent said pusher from being restored to its initial position until the coin has been ejected and the dog 105 restored to its initial position, said last named means comprising a disk carried by the rotatable shaft and having a mutilated gear portion, a mutilated gear member carried by the pusher to coöperate with the disk, said disk having its mutilated portion to release said pusher at times, and having a bearing to hold said pusher when in a predetermined position.

23. In a coin mechanism for vending machines, a unidirectionally operating shaft, a member having a cut-away portion carried by said shaft, a locking dog coöperating with said member in said cut-away portion to lock the shaft from rotation, a coin pusher, means carried by said dog to be engaged by a coin to release the dog from said member at times, combined with means carried by the operating shaft and connected with the pusher for moving the pusher from an initial position to the end of its operating stroke and locking the pusher in such position at the end of its operating stroke for a prede-

terminated time, and a bearing adapted to be engaged by said pusher when in its locked position.

24. In a vending machine, a uni-directionally rotatable operating shaft, a member thereon having a locking dog receiving groove, a locking dog, a pusher, said dog and pusher having coin engaging portions, means normally tending to hold the pusher in one position, means co-operatively connecting the pusher with the operating shaft to move the pusher and cause a coin to release the dog from its groove, a coin chute adapted to receive several coins and delivering them to the pusher and dog, and means to prevent a second coin passing from the chute into operative position into the coin engaging portion of the pusher until after the dog again enters the groove of said shaft member.

25. In a vending machine, a uni-directionally rotatable operating shaft, a member thereon having a locking dog receiving groove, a locking dog, a pusher, said dog and pusher having coin engaging portions, means normally tending to hold the pusher in one position, means co-operatively connecting the pusher with the operating shaft to move the pusher and cause a coin to release the dog from its groove, a coin chute adapted to receive several coins and delivering them to the pusher and dog, a member projectable into the path of the coins through the chute, and means for holding said member in the path of the coins at times to prevent a second coin leaving the chute until the dog enters the groove in the shaft member and the first coin has been released.

26. In a vending machine, a uni-directionally rotatable operating shaft, a member thereon having a locking dog receiving groove, a pivoted dog normally engaging said member in said groove, to lock the shaft from rotation, a pusher, said dog and said

pusher each having coin engaging portions, means normally tending to hold the pusher in one position, said pusher being normally disconnected from the operating shaft, means on the operating shaft for engaging the pusher to move it in one direction and cause a coin to release said dog from said groove in said shaft member, a coin chute for delivering coins to the pusher and dog, a member projectable in the path of the coins through the chute, and means for holding said projectable member in the path of the coins to prevent a second coin coming into operative position until the prior coin is discharged and the locking dog has again entered its locking groove in the shaft member.

27. In a vending machine, a uni-directionally rotatable operating shaft, a member thereon having a locking dog receiving groove, a pair of coin engaging elements adapted to co-operate with a coin, one of said coin engaging elements having a dog portion to normally enter the groove in the shaft member and prevent rotation of the shaft, the other coin engaging element being reciprocable, means carried by the shaft member for engaging the reciprocable coin engaging element to actuate the same, means normally tending to hold said reciprocable coin engaging element in one position, a coin chute for delivering coins to said coin engaging elements, and means controlled by one of said coin engaging elements and projectable into the path of the coins through the chute to prevent a second coin coming into operative position until said dog portion re-enters said groove on said shaft member to again lock the shaft from rotation.
